US00D742677S

(12) **United States Design Patent**
Smith et al.

(10) **Patent No.:** US D742,677 S
(45) **Date of Patent:** ** Nov. 10, 2015

(54) **CHAIR**

- (71) Applicant: **Steelcase Inc.**, Grand Rapids, MI (US)
- (72) Inventors: **Bruce M. Smith**, East Grand Rapids, MI (US); **Glen Oliver Löw**, Hamburg (DE); **James N. Ludwig**, East Grand Rapids, MI (US); **Robert J. Battey**, Middleville, MI (US); **Gordon J. Peterson**, Rockford, MI (US); **Richard N. Roslund, Jr.**, Jenison, MI (US); **Russell T. Holdredge**, Alto, MI (US); **Todd D. Krupiczewicz**, Alto, MI (US); **Nathan R. Brock**, Alto, MI (US)
- (73) Assignee: **Steelcase Inc.**, Grand Rapids, MI (US)
- (**) Term: **14 Years**
- (21) Appl. No.: **29/518,046**
- (22) Filed: **Feb. 19, 2015**

Related U.S. Application Data

- (63) Continuation of application No. 14/029,141, filed on Sep. 17, 2013, now Pat. No. 9,027,998, which is a continuation of application No. 29/432,765, filed on Sep. 20, 2012, now Pat. No. Des. 697,726.

(57) **CLAIM**

We claim the ornamental design for the chair, as shown and described.

DESCRIPTION

FIG. 1 is a perspective view of a chair embodying the present invention;

FIG. 2 is a front view of the chair;

FIG. 3 is a first side view of the chair;

FIG. 4 is a second side view of the chair;

FIG. 5 is a rear view of the chair;

FIG. 6 is a top view of the chair; and,

FIG. 7 is a bottom view of the chair.

The broken lines shown in the drawings are for illustrative purposes only and form no part of the claimed design.

1 Claim, 7 Drawing Sheets
